UNITED STATES PATENT OFFICE.

FRIEDRICH E. HELD, OF CHICAGO, ILLINOIS.

DESIGN FOR BILLIARD POOL-TABLES.

Specification forming part of Design No. **7,165**, dated February 10, 1874; application filed January 28, 1874.
[Term of Patent 3½ years.]

To all whom it may concern:

Be it known that I, FRIEDRICH E. HELD, of Chicago, in the county of Cook and State of Illinois, have invented a Design for Billiard Pool-Tables, of which the following is a specification:

The nature of my design is fully represented in the accompanying photographic illustrations, to which reference is made, and in which—

Figure 1 is a perspective view of the table. Fig. 2 is a perspective view of the top, looking down on it from one end.

A represents the frame of my table, having two parallel sides and pointed arched ends,

formed by an arc of a circle springing from each end of such sides, and meeting the arc from the opposite side of the table. B is the top or table proper, inclosed by the cushioned frame. The table has six pockets, d, one at each end, and one at the intersections of the sides and ends.

What I claim as my invention is—

A design for a billiard pool-table, having two parallel sides and pointed segment ends, substantially as shown and set forth.

FRIEDRICH E. HELD.
